UNITED STATES PATENT OFFICE.

FREDERICK L. H. SIMS, OF TORONTO, ONTARIO, CANADA, ASSIGNOR TO THE DIAPHONE SIGNAL COMPANY, LIMITED, OF TORONTO, CANADA.

KEY-BOLT.

1,266,334.

Specification of Letters Patent. Patented May 14, 1918.

Application filed February 15, 1916. Serial No. 78,465.

To all whom it may concern:

Be it known that I, FREDERICK L. H. SIMS, of the city of Toronto, in the county of York, Province of Ontario, Canada, have invented certain new and useful Improvements in Key-Bolts, of which the following is a specification.

My invention relates to bolts intended particularly for fastening rail joints and employing a key passing through a slot in the bolt as in my prior United States Patent No. 1,000,445 bearing date of August 15th, 1911, and my object is to increase the holding capacity of the bolt to the maximum possibly attainable, having reference to the size of the holes in the rail web and splice bars employed.

My invention may be briefly described as follows: In addition to using the highest quality of material and utilizing the best methods of construction and tempering, I employ a special modification in the form of the stem of the bolt which enables me to avoid any diminution in the area of metal in the cross section of the bolt where the slot occurs and without interfering with its free passage through the standard forms of holes in the rail web and splice bars.

The invention is hereinafter more particularly described and is illustrated in the accompanying drawings in which—

Figure 1 is a plan view of the blank from which the bolt is formed;

Fig. 2 a side elevation of the same;

Fig. 3 a plan view of the finished bolt;

Fig. 4 a horizontal section showing the key in position;

Fig. 5 a cross section through the cylindrical part of the bolt;

Fig. 6 a face view of part of the front splice bar with the bolt in section;

Fig. 7 a similar view showing a modification of the hole in the splice bar; and

Fig. 8 a vertical section through a rail and splice bar with one of my bolts in position.

In the drawings like numerals of reference indicate corresponding parts in the different figures.

In standard practice the web of the rail is drilled for the passage of the bolt, and in an 80 lb. rail using $\frac{5}{8}$ " bolts, the circular hole drilled in the web has a diameter of $1\frac{1}{16}$ " allowing an annulus for expansion and contraction of the web about the bolt of $\frac{3}{16}$ " each way more or less. In the splice bars

used with such a rail, the holes are based on a 1" circle but are elongated, the forms shown in Figs. 6 and 7 being two that are commonly employed. In Fig. 7 the hole is shown as ellipsoidal in form, and in Fig. 6 lozenge shaped with rounded corners. These elongations of the holes are used to receive the snugs which are formed about the part of the stem of the ordinary bolt immediately adjacent to the head, thus holding the stem of the bolt from turning when the nut is being tightened.

I take advantage of the fact that, with these standard forms of holes in the rail webs and splice bars, a bolt with slot and key need not be of circular cross section throughout its length, and so shape the portion of the stem in which the slot is formed as to secure the same cross sectional area of metal at this portion as through the solid portion of the stem near the head.

The exact shape of the slotted portion of the bolt depends on the form of the hole in the splice bar with which the bolt is to be employed. (See Figs. 6 and 7).

One form of the bolt is formed from the blank shown in Figs. 1 and 2. The blank, when the slotted portion is shaped in section to pass through an ellipsoidal hole in a splice bar as shown in Fig. 7, comprises a half round bar having the central portion 1 reduced in thickness for a length substantially equal to twice the length of the slot in the finished bolt. This reduction in thickness is formed by displacing the metal transversely of the blank instead of longitudinally, so that while the cross sectional shape of the blank at its central portion is changed in form, the area remains the same. The change of form must be such as will not make the width at this point greater than the diameter of the hole in the rail web, an ellipsoidal form such as shown in the cross sections being preferable.

The blank as shown may be formed by rolling, stamping, or forging as may seem best. The bolt is formed from the blank by bending it at the middle to bring the parts together as shown, and the end of the cylindrical portion 2 of the bolt so formed upset to form the head 3. On the head may be formed the guide teat 4, part on each half of the head. This guide teat serves to guide the user as to the proper direction for the insertion of the key.

The slotted portion 5 of the bolt, it will be seen, has substantially the same diameter transversely of the slot as the cylindrical portion 2, but its diameter depthwise of the slot is materially greater. The end 6 of the slot distant from the head is inclined as shown to fit the tapered side of the key 7. The underlying principle of construction being the maintenance of the same cross sectional area of metal in the slotted portion of the bolt as in the cylindrical portion, while insuring that the deformed portion will pass freely through the hole in the web of the rail and preferably fits the hole in the splice bar so that it will not accidentally shift its position rotatively before the key is driven, it is evident that the shape of the half cross sections of the slotted portion may be considerably varied. For instance, in Fig. 6 in which a splice bar with a lozenge shaped hole is shown the metal displaced in forming the slot increases the diameter of the bolt in an inclined direction transversely of the slot instead of in the direction of the depth of the slot.

Other variations will readily occur to the mind of any skilled mechanic which would fall under the scope of my invention as defined in the appended claims.

The halves of the bolt may be welded together if desired, but it will be found that the bolt is fully as strong with the split extending from the head through the cylindrical portion of the bolt to the adjacent end of the slot.

The particular shape of the bolt is of great advantage as it is almost twice as strong as the ordinary screw bolt which loses a very considerable percentage of its effective cross sectional area due to the threading, and so also a slotted bolt as shown in my prior patent having circular external cross sectional contours for the whole length of its stem loses almost the same proportion of strength as the threaded bolt. The bolt disclosed in the present application loses nothing, the strength at any point in its

length being as great as is possible, while leaving the necessary clearance where the bolt passes through the web of the rail. Further, the changed shape of the bolt in the slotted portion enables me to dispense with the snugs specified in the prior patent referred to, as it serves to hold the bolt from turning in the splice bar while the key is being driven or otherwise manipulated.

What I claim as my invention is:

1. A substantially cylindrical bolt provided with a head and a stem, the portion of the stem remote from the head having a substantially flat sided slot formed longitudinally therein, said slotted portion being increased slightly in periphery to give a cross sectional area of metal therein substantially equal to that in the non-slotted portion of the stem.

2. A blank for a slotted key bolt comprising a metal bar with a flat face having the middle portion of its flat face offset, the cross section of the metal in the central portion being substantially equal to that in the end portions.

3. A blank for a slotted key bolt comprising a half-round metal bar having its middle portion reduced in thickness and increased in width to maintain substantially the same cross section of metal in the portion of reduced thickness as in the other parts of the bar.

4. A blank for a slotted key bolt comprising a half-round metal bar having its middle portion reduced in thickness and increased in width in semi-ellipsoidal form to maintain substantially the same cross section of metal in the portion of reduced thickness as in the other parts of the bar.

Signed at Toronto, this 10th day of February, A. D. 1916, in the presence of the two undersigned witnesses,

FREDERICK L. H. SIMS.
